PEEP SIGHT FOR FURNACES

John Blizzard, Garden City, N. Y., assignor to
 Foster Wheeler Corporation, New York, N. Y.,
 a corporation of New York

Application August 7, 1936, Serial No. 94,751

13 Claims. (Cl. 126—190)

My invention relates to furnaces, and an improved means for permitting observation of internal furnace conditions, and the action of the burning gases on the refractory walls of a high temperature furnace chamber, and on any tubes or other devices disposed therein.

The invention is particularly applicable to furnaces which are wholly or partially surrounded by an air duct or air chamber, in which the pressure is higher than that existing in the furnace, and in which an aperture or peephole of special design, comprising a sight tube and nozzle member, opens to the atmosphere in the boiler room or firing isle and extends inwardly therefrom through the air duct and refractory furnace wall to the furnace, whereby a clear vision may be had into the furnace chamber whenever desired, without discomfort or injury and without the use of any interposed transparent material such as glass or mica.

In operation, such devices depend on the pressure differential existing between the air duct and the furnace to create a flow of air from the air duct of sufficient momentum to oppose any flow of gases from the furnace, and further depend upon a Venturi shaped nozzle assembly and diffuser to force the air from the air duct through the peephole into the furnace at the desired velocity. Apparatus of the kind described is broadly disclosed in, and forms the subject matter of the application of Hugh E. Carleton, Serial No. 89,287, filed July 7, 1936, now Patent No. 2,105,309, granted January 11, 1938.

The present invention constitutes an improvement thereon, and includes a damper for shutting off the flow of air from the air duct to the furnace during the periods when visual access to the furnace is not desired, which is highly desirable from the standpoint of combustion. Also, the arrangement is such that the opening to the peephole in the boiler room or firing isle cannot be opened for use until after the damper has been moved to the fully open position, thus first establishing a flow of air duct into the furnace and preventing possible injury to the operating personnel by an outward blast of furnace gases or preheated air, which would be the result if the order of the operation were reversed, due to the relatively high pressure existing in the air duct and furnace chamber.

For a better understanding of the particular features that characterize my invention, reference may be had to the following description, considered in connection with the accompanying drawing forming a part thereof and in which:

Fig. 1 is a vertical sectional view of a preferred form of apparatus embodying the invention, taken substantially on line 1—1 of Fig. 2;

Fig. 2 is an elevation of the outer end of the apparatus, as shown in Fig. 1; and

Fig. 3 is a transverse sectional view of the apparatus taken on line 3—3 of Fig. 1.

Like reference characters refer to like parts throughout the several views.

Referring to the drawing, particularly Fig. 1, reference character 10 designates the inner refractory lining of a furnace chamber having an outer lining of suitable refractory material, while 12 and 12' indicate the inner metallic casing walls of an air duct or chamber 13 which may entirely surround the furnace or may be disposed on and exteriorly of, one or more walls thereof. The outer wall is formed by heat insulating material designated 14 and outer metallic casing 15. Suitable means are provided to maintain a pressure in the air chamber which is higher than the pressure in the furnace, or that of the surrounding atmosphere.

The peephole arrangement selected for illustration, includes a tapered sight tube 16 having an inner end portion 16' and a laterally extending annular flange at its outer end. The inner end of the sight tube extends into the throat or reduced portion 25 of a nozzle member 23 which is secured by bolts 24 and 24' to casing 12, and forms in combination with an enlarged furnace opening 26, a Venturi shaped nozzle assembly and diffuser which is arranged and adapted to provide when the peephole is in use, the desired volume and velocity of air flow therethrough from the air chamber to the furnace, and at the same time to permit a wide range of vision within the furnace when the sight tube cover plate 17 is removed. If desired, the nozzle member 23 may be arranged to extend entirely through the furnace wall, in which event a flared aperture in the furnace wall may not be necessary. Cover plate 17, which opens to the boiler room or firing isle, is secured to an intermediate portion of a latch 18 by a pin 19, and the latch is hinged at one end by pin 20 on spaced studs 20' extending from the annular flange on the sight tube 16. The other end of the latch 18 is provided with a slot 18' which receives a swinging bolt 21 secured to said annular flange. As shown in the drawing, swinging bolt 21 also passes through a slot 31' in a lever arm 31 forming a part of the damper means hereinafter described, and both the lever arm and the cover plate 17 are secured in closed position by a wing nut 21' threaded on the bolt 21.

The sight tube 16 is supported on the outer wall of the air chamber by means of the annular flange thereon and by bolts 22 that pass through the flange and the outer wall.

5 Reference character 27 designates a thin, generally triangular or segmental shaped metal disc, or damper, fixed to squared portion 34 of an operating shaft 28 by washers 35 and nuts 36 and 37. The cylindrical inner end 29 of shaft 10 28 is supported by bearing block 38 and rotates therein, while the outer end 30 passes through the annular flanged portion of sight tube 16 and is supported thereby for rotation in gland 40. Air leakage through the gland is prevented by 15 packing 39. The lever arm 31 is fixed to operating shaft 28 by cap screw 33 and is operated by handle 32. The damper 27 is received by a narrow transverse slot or groove 42 disposed in the nozzle member 23 inwardly of the inner end 16' 20 of sight tube 16, and is adapted for a limited rotary movement therein when operated by shaft 28 and lever arm 31. An orifice 41 in damper 27 corresponds substantially in diameter to the diameter of the throat of the nozzle member. 25 The arrangement is such that by rotating the damper through a relatively small arc or range, transversely to the axis of the nozzle member, either the flow of air to the furnace can be entirely cut off, or the orifice 41 can be brought in 30 axial alignment or register with the throat of the nozzle member, and a flow of air established from the air duct to the furnace. When in the fully open position, as indicated by position A of the damper in Fig. 2 of the drawing, stop nut 43 on 35 damper 27 is in contact with the outer wall of the nozzle member, thereby preventing movement of the damper beyond fully open position.

As illustrated in the drawing, the damper is closed, and all flow from the air duct to the furnace is cut off; both the lever arm 31 and cover plate 17 of the sight tube are securely held in closed position by latch 18, swinging bolt 21 and wing nut 21' threaded thereon. When it is desired to use the peephole, wing nut 21' is loosened 45 and the lever arm 31 is moved upwardly to the right, as shown by dot and dash lines in Fig. 2, until further movement is prevented by the stop nut 43, in which position the lever will be clear of the cover plate. The bolt 21 is then swung 50 free of the latch 18, and the latch and the cover plate are swung downwardly away from the outer end of the sight tube, thus permitting a clear vision through the peephole to the furnace without discomfort or risk of injury due to a sudden blast of hot air or furnace gases. When it is no 55 longer desired to use the peephole, the damper is moved to closed position and the several parts associated therewith are returned to the positions shown in the drawing.

60 It is to be understood that changes may be made in the form and structure of the apparatus herein described and disclosed, without departing from the principles of the invention which is not to be limited except by the scope of the appended claims.

65 What I claim is:

1. In a furnace having an air chamber outside at least one wall thereof, means for observing combustion and internal furnace conditions comprising a sight tube, a nozzle member arranged to conduct air from the air chamber to the furnace and cooperating with the sight tube in such manner as to permit observation of the furnace interior through the sight tube and nozzle member, and a shut-off damper for the nozzle mem- 70 ber, and a shut-off damper for the nozzle mem- 75

ber movable transversely of the axis of the nozzle member.

2. In a furnace wholly or partially surrounded by an air chamber, a peephole assembly comprising a nozzle member extending between the air chamber and the furnace, a sight tube extending through the wall of the air chamber inwardly to the throat of the nozzle member, and a damper for the nozzle member disposed inwardly of the furnace end of said sight tube for controlling the flow of air through the nozzle member from said air chamber to the furnace. 5

3. In a furnace having an air chamber outside at least one wall thereof, means for observing combustion and internal furnace conditions therein, comprising a nozzle member for conducting air from the air chamber to the furnace, a sight tube extending through the outer wall of the air chamber and cooperating with the nozzle member, a cover for the outer end of the sight tube, and a damper for the nozzle member operable independently of the sight tube and its cover. 15

4. In a furnace having an air chamber outside at least one wall thereof, means for observing combustion and internal furnace conditions therein, comprising a nozzle member for conducting air from the air chamber to the furnace, a sight tube extending through the outer wall of the air chamber and cooperating with the nozzle member, a cover for the outer end of the sight tube, a damper for the nozzle member, and means independent of the sight tube and its cover for operating the damper, said damper operating means being disposed so as to prevent movement 35 of the sight tube cover to open position when the damper is in closed position.

5. In a furnace having an air chamber outside at least one wall thereof, means for observing combustion and internal furnace conditions therein, comprising a nozzle member for conducting air from the air chamber to the furnace, a sight tube extending through the outer wall of the air chamber and cooperating with the nozzle member, a cover for the outer end of the sight tube, a damper for the nozzle member, means independent of the sight tube and its cover for operating the damper, said damper operating means being disposed so as to prevent movement 45 of the sight tube cover to open position when the damper is in closed position. 50

6. In a furnace having an air chamber outside at least one wall thereof, a peephole for observing internal furnace conditions comprising a nozzle member supported by the furnace wall, a sight tube extending through the wall of the air chamber and disposed in axial alignment with the nozzle member, a cover plate for the outer end of said sight tube, and a damper for said nozzle member movable transversely of the axis of said nozzle member for controlling the flow of air therethrough, and common means for securing said cover plate and said damper in closed position. 60

7. In a furnace having an air chamber outside at least one wall thereof, a peephole for observing internal furnace conditions comprising a nozzle member arranged to conduct air from the air chamber to the furnace, a sight tube in axial alignment with the nozzle member, a cover plate for the outer end of said sight tube, a damper for said nozzle member disposed inwardly of the furnace end of said sight tube, and common means for securing said cover plate and damper in closed position. 65

8. In a furnace having an air chamber outside 75

- 5 at least one wall thereof, a peephole for observing internal furnace conditions comprising a nozzle member arranged to conduct air from the air chamber to the furnace, a sight tube extending through the wall of the air chamber to the throat of the nozzle member, a cover plate for closing said sight tube, a damper for said nozzle member movable transversely of the axis thereof for controlling the flow of air therethrough, a lever for opening and closing said damper, and common means for securing both the damper and cover plate in closed position, the arrangement being such as to prevent the opening of said cover plate when said damper is closed.
- 10 9. In a furnace having an air chamber outside at least one wall thereof, a peephole for observing internal furnace conditions comprising a nozzle member arranged to conduct air from the air chamber to the furnace, a sight tube extending through the wall of the air chamber to the throat of the nozzle member, a cover plate for closing said sight tube, a damper for said nozzle member, an orifice in the damper, and means for rotating said damper transversely of the axis of said nozzle member whereby the orifice is moved into or out of alignment with the nozzle member, thereby permitting or preventing flow of air through the nozzle member from said air chamber to the furnace.
- 15 10. In a furnace having an air chamber outside at least one wall thereof, a peephole for observing internal furnace conditions comprising a nozzle member arranged to conduct air from the air chamber to the furnace, a sight tube extending through the wall of the air chamber to the throat of the nozzle member, a cover plate for closing said sight tube, a damper for said nozzle member disposed inwardly of the furnace end of said sight tube, an orifice in the damper having a flow area substantially equal to the flow area of the throat of the nozzle member, means for rotating said damper through a limited arc to open or close said nozzle member, and common means for securing the cover plate and damper in closed position, said means for rotating the damper being

arranged and disposed so as to prevent the opening of said cover plate before said damper has been rotated to the fully open position.

11. In a furnace having an air chamber outside at least one wall thereof, a peephole for observing internal furnace conditions comprising a nozzle member arranged to conduct air from the air chamber to the furnace, a sight tube extending through the wall of the air chamber to the throat of said nozzle member, a cover plate for closing said sight tube, a damper for the nozzle member disposed inwardly of the furnace end of said sight tube, a shaft extending through the wall of the air chamber and operably connected to the damper, an operating lever fixed to the shaft at its outer end and arranged to overlap said cover plate, and common means for securing the lever and cover plate in closed position, the arrangement being such that said cover plate cannot be removed from said sight tube until the damper is moved to a position in which the nozzle member is open.

12. In a furnace having an air duct outside at least one wall thereof, means for observing combustion and internal furnace conditions comprising a nozzle in a wall of the furnace, a sight tube extending through the wall of the air duct and having its inner end so disposed with respect to the nozzle that fluid flow through the latter causes air flow inwardly through the tube, and a shut off damper for the nozzle member movable transversely of the axis of the nozzle member.

13. In a furnace having an air duct outside at least one wall thereof, means for observing combustion and internal furnace conditions comprising a nozzle in a wall of the furnace, a sight tube extending through the wall of the air duct and having its inner end so disposed with respect to the nozzle that fluid flow through the latter causes air flow inwardly through the tube, and a damper for the nozzle member disposed inwardly of the furnace end of said sight tube for controlling the flow of air through the nozzle member from said air chamber to the furnace.

JOHN BLIZARD. 45
